UNITED STATES PATENT OFFICE.

CHARLES GAINER TURNER, OF ATLANTA, GEORGIA.

DESIGN FOR A DISPLAY CONTAINER.

Application filed June 23, 1921. Serial No. 479,928. Term of patent 7 years.

To all whom it may concern:

Be it known that I, CHARLES GAINER TURNER, a citizen of the United States, residing at Atlanta, in the county of Fulton and State of Georgia, have invented a new, original, and ornamental Design for Display Containers, of which the following is a specification, reference being had to the accompanying drawing, forming part thereof.

The figure is a perspective view of the container, showing my new design.

I claim:

The ornamental design for a display container, as shown.

CHARLES GAINER TURNER.
